UNITED STATES PATENT OFFICE.

JOSEPH H. WILLIAMS, OF WALLACE, IDAHO.

ROTARY ENGINE.

1,155,536.

Specification of Letters Patent.

Patented Oct. 5, 1915.

Application filed November 9, 1914. Serial No. 871,105.

To all whom it may concern:

Be it known that I, JOSEPH H. WILLIAMS, a citizen of the United States, residing at Wallace, in the county of Shoshone, and State of Idaho, have invented certain new and useful Improvements in Rotary Engines, of which the following is a specification.

This invention relates to improvements in engines and has to do more particularly with the rotary type in which the working cylinders revolve about a common axis.

It is one of the objects of this invention to provide a rotor with removable sections in which the working cylinders are formed so that in case of renewal or repair, one working cylinder section could be removed from the rotor without necessitating detachment of the latter.

20 A further object of the invention is to provide cam devices mounted about the axis of rotation of the rotor and coacting with means for returning the pistons of the cylinders to a starting position, subsequent to actuation of the pistons by the motive fluid, cams also being provided for coaction with devices for supplying a forced feed of the motive fluid and controlling exhaust from the working cylinders.

30 In some embodiments of the invention where a forced or pressure supply of the motive fluid is necessary, it is an object of the invention to provide mechanism for supplying the motive fluid or explosive fuel under pressure to the working cylinder feeding means.

The device of my invention has many other objects and features which will be more fully described in connection with the 40 accompanying drawings, and which will be more particularly pointed out in and by the appended claims.

In the drawings:—Figure 1 is a view in side elevation embodying one form of my improved rotary engine. Fig. 2 is a view partly in elevation and partly in section showing the working cylinders and pistons and the cam actuated means for restoring the pistons to working positions during their 50 travel about the common axis. Fig. 3 is a view partly in side elevation, looking in a direction opposite from the direction from which Fig. 1 is viewed, parts being shown in section. Fig. 4 is a sectional view on line 4—4 of Fig. 3. Fig. 5 is a sectional view on line 5—5 of Fig. 3. Fig. 6 is a sectional

view on line 6—6 of Fig. 3. Fig. 7 is a sectional view on line 7—7 of Fig. 3. Fig. 8 is a sectional view on line 8—8 of Fig. 3. Fig. 9 is a sectional view on line 9—9 of Fig. 4. Fig. 10 is an enlarged view in elevation of two of the improved cams for actuating certain of the devices. Fig. 11 is a view in elevation looking in the direction of arrow 11 of Fig. 7.

Like characters of reference designate similar parts throughout the different figures of the drawings.

As illustrated, 1 designates a base having bearing uprights 2 and 3 for supporting the 70 rotary mechanism.

A rotor shaft 4 is journaled in the upright bearings 2 and 3 for rotation therein and fixed upon rotor shaft 4 is a rotor, designated as a whole at 5. The rotor 5 is provided with a centrally disposed hub 6 from which a circular web 7 extends radially, the web 7 being enlarged as indicated at 8 to form an annular periphery. The enlarged head portion is cut away at spaced annular 80 points for removable attachment of working cylinder sections 9, thereto, which are adapted to be secured by means such as bolts 10 and 11 against displacement laterally in either direction with respect to the rotor 5. 85 The juncture configuration of the sections 9 with respect to the rotor 5 will be clearly seen by reference to Figs. 5, 7 and 8, and need not be described in detail. Each section 9 has formed therein a working cylinder 12, which is open at one end and closed at the other end, as will be clearly seen by reference to Fig. 3. A working piston 13, is provided in each cylinder, and the piston rod 14 of the piston extends toward and 95 through the open end of the cylinder and is indicated at 14. A piston rod guide and spring abutment 15 is mounted near the open end of the cylinders 12 and the piston rod 14 extends through said guide 15. The 100 end of the piston rod 14 is shaped to form a substantially spherical thrust or bearing ball 16, and slightly inside of the thrust or balled end 16 I provide a spring abutment or collar 17. Between the spring abutment 105 17 and the abutment 15, is interposed an expansively acting spring 18 which normally acts to move the piston 18 toward the open end of the cylinder 12. It will also be understood that this movement is in the direction of the working stroke of the piston 13.

When the motive fluid is in the form of

a combustible gas, or in other words, when the engine is used as an explosive engine, then it is necessary to provide means for actuating the piston 13 so as to compress the admitted explosive fluid prior to ignition. It may be stated at this point, that ignition means is not shown in the present case as it is intended to file a separate application upon ignition means which is especially adapted for this particular type of engine. Furthermore, my improved engine is adapted for use either with an explosive gas or with steam, but the description following will be confined substantially to the use of explosive gas. As all of the cylinders and pistons, which will hereinafter be termed the working cylinders and pistons, are the same in structure and operation, only one need be described in detail.

Piston retracting mechanism includes a retractor lever 19 which is provided with an elongated socket 20 for engagement with the thrust end 16 of the piston rod 14. The retractor lever 19 is mounted upon a spindle 21 which is journaled in the rotor 5 and which projects laterally therefrom as indicated in Fig. 6. A cam controlled link 22 is connected with the retractor arm or lever 19, as indicated at 23, at one end of said link, the other end of said link being connected by a pin 24 in a slot 25 of a cam controlled lever 26. The cam controlled lever 26 is pivotally mounted at 27 to the web 7 of the rotor 5, between the ends of said lever 26, that end opposite the slotted end with respect to the pivot 27 being provided with a roller 28. The roller 28 is arranged for engagement and actuation with and by a retractor cam 29, which as shown more particularly in Fig. 4, is mounted on the bearing upright 3. The cam 29 is provided with a high point 30 which serves to actuate the lever 27 in such a manner as to move the retractor arm or lever 19 toward the closed end of the cylinder 12 so as to retract working piston 13 toward a starting working position, closely adjacent the closed end of the working cylinder.

It is desirable, and in some cases necessary, not only to limit but to adjust the extent of retraction of the working piston 13, under the action of retractor spring 18, and novel means is provided to perform this function.

A threaded adjusting stem 31 extends through and has threaded connection with a lug 32 on the rotor 5, and is provided with a finger grip 33 for adjusting said stem. The remaining end of the adjusting stem 31 has a ball and socket connection at 34, with the retracting arm or lever 19, sufficiently off center with respect to the spindle 21 so that when the stem 31 is turned in one direction, it will cause the socket end of the

retractor arm 19 to approach the cylinder 12. Thus irrespective of the cam 29, the spring 18 will have its retracting movement limited by the extent to which the retractor arm 19 can swing away from the closed end of the working cylinder 12. In the embodiment shown, the rotor is provided with four removable sections providing four working units each consisting of a working cylinder and a working piston and its accompanying mechanism. For convenience of identification in describing the operation at various annular points as the rotor revolves, these working units will be identified by letter characters *a*, *b*, *c* and *d*.

Irrespective as to whether steam or an explosive gas is used as a motive fluid, the working piston of unit *a* is in a starting working position and will have compressed a charge of explosive fuel when in the position shown. Assuming that at this point ignition takes place, the closed end of the cylinder will be thrust away from the working piston to impart a rotary thrust to the rotor 5. As the rotor 5 revolves about the fixed cam 29, the roller 28 will ride off from the high point 30 and down onto a receding portion of the cam 29 as indicated by unit *b*. This will permit a movement of lever 26, which added to the slotted connection of link 22, will permit retractor arm 19 to move into the position shown at unit *b*. As the rotor revolves to the position occupied by unit *c*, the roller 28 thereon will be approaching a gradually increasing portion of the cam 29 and when unit *d* has been reached, the exhausted gases will be discharged from the working cylinder by reason of the fact that the roller 28 is riding up upon a high part of the cam 29. Now it is the intention to ignite the charge at every second revolution and therefore after the rotor has been actuated upon ignition, it will make one complete revolution in its working thrust to completely discharge the exhaust gases, and upon its second revolution it will then compress a charge and be ready for ignition when in the position of the unit *a*. However, if steam is used as a motive fluid, then, and in that event, a working stroke may be had at each revolution.

In cases where explosive gas is used as a motive fluid, the device of my invention not only contemplates simply a pressure supply but also a pressure feed into the cylinders. I will first describe the mechanism for supplying the gas under pressure. The right hand end of rotor shaft 4 is enlarged to provide a cylinder carrying head 35 and there is preferably provided in said head a plurality of supply cylinders and pistons which provide for a constant supply under pressure of explosive fuel for the working cylinders. As each of the supply cylinders

and its appurtenant parts are identical in structure and operation, only one need be described in detail.

First referring to the initial supply of gas, 36 designates a gas supply pipe provided with a valve 37. The supply pipe 36 delivers to a fitting 38 which is connected with a delivery gas pipe 39. Delivery gas pipe 39 delivers to a removable head 40 and more particularly to an intake chamber 41 formed therein. Air supply ports 42 also deliver to said chamber 41. A valve stem 43 extends through the fitting 38 and is provided with a hand grip 44, on one end thereof, the other end of said stem 43 being provided with a closure 45 which engages a main inlet port 46 to control passage of air and gas thereto. Inlet port 46 delivers to initial supply ports 47 and the latter deliver to valve chambers 48. Valve chamber 48 opens to supply cylinder 49 and entrance of the gas thereto is controlled by a valve 50. The valve 50 is provided with a valve stem 51 which extends through a guide 52 and which is provided on its extreme end with an abutment 53. A spring 54 is interposed between the abutment 53 and the guide 52 to normally close the valve 50 against its seat 55 to shut off supply to the supply cylinder 49. Movement of the piston in supply cylinder 49 serves to unseat valve 50, against the action of spring 54, as shown more particularly in Fig. 9. A supply piston 56 reciprocates in supply cylinder 49 and is provided with a piston rod 57 which extends through and is guided in the cylinder head 58. Piston rod 57 is pivotally connected with an eccentric rod 59 which is connected with an eccentric 60. Eccentric 60 is mounted upon a shaft 61, supported on rotor shaft 4 in any desirable manner, and provided with a beveled gear 62 adapted to mesh with a fixed beveled gear 63. Fixed beveled gear 63 is mounted upon upright bearing 3 in a manner to be in engagement with all of the gears 62, which are employed, as the gears 62 rotate with rotor shaft 4.

It will now be clear that as the supply pistons 56 are reciprocated, they will draw in charges of gas into the supply cylinders 49 and also discharge the intaken gas therefrom. The discharge of intaken gas from said supply cylinders is through discharge ports 64 which open to a valve controlled supply port 65. This port 65 is located in removable head 40 and is controlled by a valve 66 which is held by a spring 67, normally, in a closed position. The mixture from axial port 65 delivers into a chamber 68 which communicates with a manifold axial supply port 69 extending lengthwise of rotor shaft 4. Said port 69 delivers to radial ports 70, in the rotor shaft 4, which register with radially disposed ports 71 in the rotor 5 which extend radially outward

through the web 7 and into the enlarged annular portion 8.

The ports 71 leading from the manifold port 69 each deliver to a pressure feed device, one of which is provided for each working cylinder, and which will now be described in detail. The ports 71 deliver to pressure cylinders 72, as will be seen more particularly with reference to Fig. 7. The cylinder 72 communicates with a port 73 which delivers to the working cylinder 12. A forced feed piston 74 is reciprocable in cylinder 72 and is mounted upon a piston rod 75. The piston rod 75 extends beyond the piston 74 and is provided with a valve 76, shown in an open position, and adapted to seat upon a valve seat 77, formed on one end of a sleeve which is fitted in the cylinder 72. The piston 74 is shown to be in practically an opened position, or in other words, in a position to unseat the valve 76 from the seat 77. In this position, it will be seen that the piston 74 is some distance from the terminal end 78 of the delivery port 71. As the piston 74 advances toward port 73, it will have a movement sufficient to shut off terminal 78 and compress the gaseous contents of cylinder 72 so as to force the latter into the working cylinder 12. Thus it will be seen that when the piston 74 moves toward a forced feed position, the valve 76 will always be open, and when the piston 74 is retracted from a forced feed position, the valve 76 will be seated and will close egress to the cylinder 12.

I will now describe the manner in which the piston 74 is operated to perform the function just described. The piston rod 75 is provided with a spring abutment 79 between which and the end of cylinder 72, as indicated at 80, is interposed an expansively acting spring 81. This spring functions to move the piston rod 75 in a direction to seat the valve 76 and the latter acts as a stop limiting movement of the piston rod 75 under action of the spring 81. I will next describe the mechanism for moving the forced feed piston 74 against the action of spring 81, or in other words, in a feeding direction. Referring to Figs. 7 and 11, 82 designates a bearing upright, mounted on hub 6, and in which is journaled a ratchet shaft 83. A ratchet wheel 84 is revolvably mounted on shaft 83 and is provided with tappets 85 and 86 which are adapted to successively engage the capped end 87, of piston rod 75. The engagement of said tappets with piston rod 75, serves to actuate the same toward a feeding position when the ratchet wheel 84 is revolved, and it will be seen by reference to Fig. 7, that the tappets are cammed so as gradually to force the piston rod 75 radially outwardly. The ratchet wheel 84 is provided with exterior ratchet teeth 87 and interior ratchet teeth 88. A spring actuated

100

105

110

115

120

125

130

135

pawl 89 engages the exterior teeth 87' to prevent rotation of the ratchet 84 in the direction opposite to the direction in which it is advanced.

5. To facilitate an understanding of the operation, it may be stated that ratchet wheel 84 is advanced in a contra-clockwise direction, looking at the same in Fig. 7. On the shaft 83 is loosely mounted a pawl carrier 90 which carries a pawl 91 which is spring actuated so as to engage the interior teeth 88. The carrier 90 is provided with an arm 92 which is pivotally connected with an actuator rod 93. The actuator rod 93 is reciprocable in a bearing 94, mounted upon hub 6. A collar 95, mounted on rod 93, forms an abutment between which and the bearing 94 is interposed a spring 96 for normally forcing the rod 93 to the left of Fig. 7. The terminal end of rod 93 is bent at an angle and is provided with a roller 97 for engagement with an actuator cam 98, the actuator cam 98 being formed on a reduced part of bearing 2 and the foregoing mechanism is so timed and arranged that at each second revolution of the rotor, the piston rod 73 will be forced into a feeding position by the tappets 85 and 86. It will be understood that reciprocation of the rod 93, will 30 act through the pawl 91 to intermittently rotate ratchet wheel 84.

A controlling device for exhaust of the contents of each working cylinder, is provided, and is shown more particularly in Fig. 8. The cylinder 12 is provided with an exhaust or egress port 99 in which is secured a valve fitting 100 having a valve seat 101. An exhaust valve 102 is adapted to seat on said valve seat 101 to close the exhaust from the cylinder 12. Valve 102 is provided with a valve stem 103 having a spring abutment 104 thereon. Between the abutment 104 and the fitting 100, is interposed an expansively acting spring 105 which normally acts to move the valve 102 into a seated position, as shown in Fig. 8. The valve stem 103 is provided with a capped end 106 which is adapted to be actuated by a bell crank lever 107. Lever 107 is pivoted to the rotor at 108 and that arm of the lever opposite the arm 107, as indicated at 109, is pivotally connected with an actuator rod 110. Actuator rod 110 is slideable in a bearing 111, mounted upon hub 6, and interposed between the bearing 111 and an abutment 112, is a spring 113 which normally acts to move the actuator 110 to the right of Fig. 8. The remaining end of the actuator 110, is bent at right angles at 114 and carries a roller 115 adapted to be actuated by a cam 116.

The cams 98 and 116 are shown more fully in Fig. 10, and it will be understood that they will be so formed as to actuate the mechanism in a manner to open valve 76 and

102, respectively, and successively, at every 65 second revolution of the rotor 5.

It is believed that the device of my invention will be clearly understood from the foregoing description, and while I have herein shown and described one specific 70 form, I do not wish to be limited thereto except for such limitations as the claims may import.

I claim:

1. In a rotary engine, a rotor including 75 working cylinders and pistons therefor, feeding cylinders in said rotor one for each working cylinder, a piston in each feeding cylinder, a valve controlling communication between each feeding cylinder 80 and its working cylinder and limiting movement of said feeding piston in a non-feeding direction, a spring for actuating said piston in a non-working direction to close said valve, and fixed cam means for 85 actuating said feeding piston in a feeding direction to open said valve, substantially as described.

2. In a rotary engine, a rotor provided with a working cylinder, a working piston 90 in said cylinder adapted for working movement under motive fluid pressure to impart rotary thrust to said rotor, a spring for retracting said piston, and means limiting retraction of said piston under the action of 95 said spring, substantially as described.

3. In a rotary engine, a rotor provided with a working cylinder, a working piston in said cylinder adapted for working movement under motive fluid pressure to impart 100 rotary thrust to said rotor, a spring for retracting said piston, means for limiting retraction of said piston under the action of 105 said spring, and mechanism for adjusting said means to vary the retractive movement of the piston, substantially as described.

4. In a rotary engine, a rotor provided with a working cylinder, a working piston in said cylinder adapted for movement 110 therein under motive fluid pressure to impart rotating thrust to said rotor, a spring for retracting said piston, means for limiting retraction of said piston under the action of said spring, and cam mechanism for actuating said means to move said piston 115 against the action of said spring to a starting position, substantially as described.

5. In a rotary engine, a rotor provided with a working cylinder, a piston in said cylinder adapted for working movement 120 under motive fluid pressure to impart rotating thrust to said rotor, a spring for retracting said piston, a retractor arm pivoted on said rotor and engaging said piston, and cam means acting through said retractor arm for limiting retraction of said piston and moving said piston to a starting position, substantially as described.

6. In a rotary engine, a rotor provided with a working cylinder, a piston in said cylinder adapted for working movement under motive fluid pressure to impart rotatory thrust to said rotor, a spring for retracting said piston, a retractor arm pivoted on said rotor and engaging said piston, a cam fixed about the center of rotation of said rotor, and a lever pivoted on said rotor and connected with said retractor arm and engaging said cam to limit movement of

said piston under the action of said spring and to return said piston, through said retractor arm to a starting position, substantially as described.

15

In testimony whereof I affix my signature in presence of two witnesses.
